SHEDDING MECHANISM OF CIRCULAR LOOMS

Frank Corbyn Hale and William Howarth, Spondon, near Derby, England, assignors to Celanese Corporation of America, a corporation of Delaware

Application June 22, 1935, Serial No. 27,834
In Great Britain July 10, 1934

11 Claims. (Cl. 139—16)

This invention relates to circular looms, having as its principal object the provision of an improved shedding mechanism therefor.

The most advantageous construction of circular loom for weaving textile fabrics being one in which the warps proceed substantially cylindrical to the point at which they are woven into fabric so that the diameter of the fabric may be large in relation to the space occupied by the loom, the shedding movement of the warp threads out of their normal line from the supply to fabric must be in a radial or substantially radial direction. The necessity for imparting such movement to the warp threads leads to difficulty in constructing shedding mechanism for a circular loom, especially as most textile fabrics have the warp threads spaced very close together, which calls for the disposition in a relatively restricted space of a great number of controlling elements necessary to bring about shedding. The difficulty above-mentioned is further increased because these elements have to be reasonably accessible to the operative for the entering of a warp or the tying-in of broken ends.

The apparatus according to the present invention provides in a simple manner for the radial movement of each warp thread and enables effective control to be obtained over all the warp threads even when these are present in very high density.

According to the invention the warp threads are controlled by light flat metal healds mounted on their edges so as to project radially outwards from a support arranged round the loom within the warp circle. The healds are mounted in a plurality of banks in the one support, each heald being free to move over a distance somewhat in excess of that necessary to divide the warp threads into a shed through which the shuttle can pass. By reason of the outward projection of the healds from their support the healds in any bank are immediately accessible from outside the loom for threading-up or replacement, and the thinness of the healds enables them to be pushed to one side and give greater accessibility to any particular heald or set of healds during threading-up.

Means are provided which tend to urge all the healds into a shedding movement in a radial direction and in connection with these means, means are provided for restraining healds in selected banks against such shedding movement so that the warp threads whose healds are free are in this way deflected to one side of the shut-

tle, while the threads whose healds are restrained remain undeflected. The shuttle then enters the space between the separated threads and completes the shed by pressing the threads apart.

The means for restraining the movement of any bank of healds can be simply a stop suitably supported to lie opposite the healds before the latter come under the action of the means tending to urge them into movement. In order to bring about the movement of the healds, the threads are engaged near to the healds on the side of the heald banks remote from the shuttles by shedding wheels projecting through the normal line of the warps so as to force the warp threads to one side of this line. All healds which are free to move partake of this movement, sliding easily in their support while those healds which encounter a stop are prevented from having the shedding movement.

In an alternative arrangement, all the healds are normally held against radial movement, means being provided in advance of each shuttle to free the healds in any selected bank or banks. Thus, the healds may be notched to engage a catch, cam means being employed to rock selected healds out of engagement with the catch in readiness for their shedding movement.

The heald stops or releasing cams are with advantage disposed at the side of the heald support opposite the side from which the healds project to control the warps, and the stops or cams are preferably placed close to the support so that the length of the healds projecting from the support when they are in contact with the stops or cams is very small. Any sideways thrust arising by reason of relative circular motion between the healds and the stops or cams is thus minimized and the light healds easily resist any tendency to bend and are still capable of sliding freely in their supports.

Any desired number of heald banks may be employed, the number depending to a large extent on the type of weave desired. Thus for example five-shaft or eight-shaft satin weaves require the use of five or eight banks of healds. Apart, however, from the multiplication of the number of banks necessary for certain weaves, the shedding mechanism is exceedingly simple in character, the healds themselves being very light in weight and readily move under the action of the shedding wheels without danger of straining the warp threads. The healds, in fact, have only to be sufficiently rigid to avoid flexing under the very light forces to which they are subjected.

Some forms of shedding mechanism according to the invention will now be described in greater detail with reference to the accompanying drawings, Fig. 1 of which illustrates in part cross-sectional elevation shedding mechanism suitable for the weaving of a five-shaft satin incorporated in a circular loom employing rotating shuttles;

Fig. 2 is a plan view of the apparatus shown in Fig. 1;

Fig. 3 is a diagrammatic part cross-sectional elevation showing the disposition of the mechanism of Fig. 1 with respect to the central shaft of the loom;

Fig. 4 is a part cross-sectional elevation of a modified form of shedding mechanism similar to that of Fig. 1;

Fig. 5 is a plan view of the apparatus shown in Fig. 4;

Fig. 6 is an end elevation of a detail of Figs. 4 and 5, while

Fig. 7 shows diagrammatically in plan view a modified detail of the apparatus shown in Fig. 2.

With reference to Figs. 1 and 3, warp threads 7 unwinding from warp beams or other supply packages (not shown) proceed downwardly to the fabric 8 along the fell 9 of which weft is laid by a number of shuttles 10 (one shown). Immediately above the level of the shuttle 10 are mounted a pair of concentric cylindrical reed-like members 11, 12, set in soft metal 13, such as lead, and supported by a spider 14 which is secured to the central shaft 15 of the loom.

The reed 11 while being of less diameter than the reed 12 is provided with the same number of dents 16, the two reeds extending axially of the loom to a height sufficient to accommodate five banks of thin warp thread controlling healds 17. Each bank of healds is supported by concentric rings 18 secured in the inner edges of the dents 16, and each heald 17 is free to slide on its edges between corresponding dents 16 of the two reeds, while being guided radially by the dents.

As shown in the drawings, each heald 17 projects outwardly from the reed 12 over a substantial distance and engages its corresponding warp thread or threads at a point removed from the reeds so as to be readily accessible for threading-up.

Situated above the level of the banks of healds 17 and in advance of each shuttle 10 is a warp shedding wheel 19 mounted for free rotation on an arm 20 outstanding from a pillar 21 which is carried round the loom at the same speed as the shuttles 10. The arm 20 is adjusted on the pillar 21 in such a manner that the edge of the shedding wheel 19 projects beyond the normal line 22 of the warp threads 7, and on being carried around the loom presses the warp threads 7 in turn, and consequently the healds 17 in connection therewith, towards the central shaft 15.

In order to prevent the inward movement, at any particular shuttle, of the healds 17 of any bank controlling warp threads which are to be divided from the rest to form a shed for reception of the shuttle, a series of stops 23 are provided, each being adapted to hold the healds in a selected bank in their normal position against inward movement under the influence of the pressed warp threads 7.

The stops 23 are in the form of short plates and are clamped in spaced relation close to and opposite the inner ends of the healds 17 on a spindle 24 depending from an extremity of a spider 25 which is rotated about the central shaft 15 by a

sleeve 26 at the same rate as the shuttles 10 and shedding wheels 19. One set of stops 23 is carried by the spider 25 slightly in advance of each shuttle 10, so that any desired stop can be set to project towards the ends of the corresponding bank of healds 17 just before and while the healds are pressed inwardly by the warp threads 7.

In Fig. 1 the third stop is shown in the operative position, the healds 17 of the third bank being held against inward movement, thereby allowing of a shedding of the warp threads 7 into two sheets 22, 28. Fig. 2, (from which the reeds 11, 12 are omitted for clarity), shows clearly in plan the respective positions of the healds which are free to slide inwardly, viz., the first, second, fourth and fifth banks, and the healds of the third bank which are maintained in normal position by the third stop 23.

When in working position, the operative edge of each stop 23 is disposed very close to the dents 16 of the inner reed 11, so that the length of the healds 17 projecting from the reed 11, when they are in contact with the stop, is very small. Any sideways thrust arising from the relative circular motion between the healds and the stops is thus minimized and the light healds easily resist any tendency to bend and are still capable of sliding freely on the rings 18 between dents 16.

As will be observed from Fig. 1 the distance between the two sheets 22, 28 of warp threads 30 is relatively narrow. The nose of the shuttle 10, however, enters the narrow space and the shuttle itself pushes the two sheets 22, 28 apart to form a shed of the requisite width, as indicated at 29, 30. After the passage of the shuttle 10 through 35 the shed the tension in the warp threads 29, 30 returns them and their healds to their normal positions in readiness for further shedding. It will be noted that the healds 17 are long enough to remain in engagement with the dents 16 and supporting rings 18 even when pulled outwardly to the fullest extent by the warp threads of the sheet 29.

With the warp threads in their normal position, viz., in the line 22, there is a slight clearance between the inner ends of the healds 17 and the operative edge of the adjacent stop 23. Therefore, when the healds are urged to move inwardly by the pressed warp threads, they can move only over the small distance between their inner ends and the stop. The stops 23 are formed with inclined portions 31 at their ends in order that any heald brought into engagement with a stop prematurely is directed smoothly by the inclined portion 31 to the outermost point of the stop without bending the heald.

If desired the stops 23 may be replaced by endless bands 32 (see Fig. 7) rotating about guide wheels 33, the guide wheels being mounted at the extremities of the spider 25 at the requisite height adjacent to the ends of the healds 17 in any bank. The guide wheels 33 may be power driven in the direction opposite to the direction of motion of the shuttles 10 and at a speed equal to the shuttle speed so that the endless bands 32 in effect roll over the ends of the healds 17 which are to be held in their normal position against the pressure of the warp threads.

With this arrangement each band 32 is enabled to act as a stop against the inwardly projecting ends of the healds 17 without exerting any sideways bending action on the healds since there is no relative motion between the healds and the part of the band engaging the healds. The guide wheels 33 may, on the other hand, be freely

mounted to allow the bands 32 to roll over the ends of the healds 17 merely by frictional contact therewith.

In the weaving of a five-shaft satin the warp threads 7 are divided amongst the five banks of healds 17 in the following manner:—

The first of five warp threads is controlled by a heald of the first bank; of the four remaining threads of each group of five, the fourth thread 10 is controlled by a heald of the second bank and the second, fifth, and third threads of the group are controlled respectively by the healds of the third, fourth and fifth banks. Thus, at the shuttle 18 shown in Figs. 1 and 2, the second warp 15 threads of the groups of five are being restrained against inward movement, while at the succeeding shuttle the fifth thread of the group will be restrained, and so on around the loom, the number of shuttles in operation being divisible by 20 five.

In the modified form of shedding mechanism shown in Figs. 4 and 5 the spider 25 (Fig. 3) carries at each of its extremities at a point in advance of each shuttle 18 a freely rotatable warp 25 shedding wheel 35 extending beyond the normal line 22 of the warp threads. On rotation of the spider 25 all the warp threads are thus pressed outwardly beyond their normal line progressively round the loom.

The warp threads are controlled by banks of healds 36 which are guided by the dents 16 of two concentric reed-like members 11, 12 as described in connection with Fig. 1. While the banks of healds 36 are supported between the 35 dents of the reed 12 by rings 18 as described in connection with Fig. 1, they are supported in the reed 11 by rings 37 of square cross-section. These rings 37 engage recesses 38 formed in each heald 36 when the warp threads are in their normal line 22, and lock the healds against outward movement.

In order to free the healds 36 of a selected bank so that the warp threads controlled thereby can be shedded outwardly under the influence of the 45 shedding wheel 35 a cam plate 39 (one shown in full line in Fig. 4) adapted to extend between the heald banks to a point adjacent to the dents 16 of the member 11 is provided in connection with each bank and is carried round the loom at 50 the desired height relatively to the heald banks on a spindle 40 depending upon each of the extremities of the spider 25.

The operative edge of each cam plate 39 is formed with an upstanding lip 41 (see Figs. 4 and 55 6) which is chamfered at 42 to a point below the level of the lower edges of the healds beneath which it runs so that as the cam plate is carried between the heald banks, the healds of the corresponding bank are lifted smoothly by the 60 chamfered portion 42 on to the lip 41 (as shown clearly in Fig. 6) and thereby freed from the locking action of the rings 37. As shown in Fig. 5 the leading edge of the cam plate 39 in connection with the shuttle 10 is set in advance of the point at which the shedding wheel 35 presses 65 against the warp threads, viz. just in front of the nose of the shuttle 10. This setting ensures that the healds of the selected bank are freed for outward movement as soon as the warp 70 threads controlled thereby are pressed by the shedding wheel 35. In Fig. 4 the cam plate 39 in connection with the shuttle 10 is shown in operation, the healds 36 of the first bank having been rocked upwardly and freed for outward 75 movement.

On release of the healds of any particular bank the warp threads controlled thereby are pushed outwardly to the position shown at 43, leaving the threads controlled by the locked healds in the normal warp line 22. As explained with reference to Fig. 1 this initial shedding of the warp threads is completed by the shuttle itself on its entry into the shed, the shuttle pushing the warp threads at 43 and 22 sideways to the requisite width, indicated at 44, 45. For this reason the 10 recesses 38 in the healds 36 are long enough to allow the locked healds to recede radially under the pressure of their warp threads. After the passage of the shuttle through the shed the tension in the warp threads 44, 45 returns them and 15 their healds to their normal positions in readiness for further shedding, the recesses 38 of the healds controlling the outwardly pushed threads re-engaging the square rings 37.

It will be understood that the spacing of the 20 healds as shown in Figs. 2 and 5 is exaggerated for clarity of illustration. In practice the healds can be thin enough to be disposed very close together, e. g. thirty or more to the inch in a five bank arrangement for the weaving of five-shaft 25 satin, the edgewise mounting of the healds ensuring rigidity in operation. The thinness of the healds and the fact that they engage the warp threads at a point removed from the reeds 11, 12 enables them to be pushed to one side to 30 give greater accessibility to any particular heald or set of healds during threading-up.

While the apparatus according to the invention has been described more particularly with reference to circular looms having rotating shuttles, it is to be understood that the mechanism may be applied to circular looms in which the shuttles are stationary while the warp threads rotate. In this latter case the shedding wheels 35 and the supports for the stops or cam plates are 40 maintained stationary with the shuttles while the healds rotate with the warp threads.

What we claim and desire to secure by Letters Patent is:—

1. Shedding mechanism for circular loom, 45 comprising a heald support disposed within the warp circle, a plurality of banks of individually movable flat warp thread controlling healds mounted on their edges within the support and projecting radially outwards therefrom so as to 50 control the warp threads from the inside of the warp circle, means between which and the healds there is relative circular motion about the loom axis for urging all the healds into a shedding movement in a radial direction progressively 55 round the loom, and means cooperating with said urging means for restraining healds in selected banks against such shedding movement so that the warp threads whose healds are free are deflected progressively round the loom while the 60 warp threads whose healds are restrained remain undeflected.

2. Shedding mechanism for a circular loom, 65 comprising a heald support disposed within the warp circle, a plurality of banks of individually movable flat warp thread controlling healds mounted on their edges within the support and projecting radially outwards therefrom so as to control the warp threads from the inside of the warp circle, means between which and the healds 70 there is relative circular motion about the loom axis for urging all the healds into a shedding movement in a radial direction progressively round the loom, and a stop mechanism cooperating with said urging means for restraining healds 75

in selected banks against such shedding movement so that the warp threads whose healds are free are deflected progressively round the loom while the warp threads whose healds are restrained remain undeflected.

3. Shedding mechanism for a circular loom, comprising a heald support disposed within the warp circle, a plurality of banks of individually movable flat warp thread controlling healds mounted on their edges within the support and projecting radially outwards therefrom so as to control the warp threads from the inside of the warp circle, means disposed outside of the warp circle and between which and the healds there is relative circular motion about the loom axis for urging all the healds into a shedding movement towards the loom axis progressively round the loom, and a stop mechanism disposed inside of the warp circle, said stop mechanism being adapted to cooperate with the urging means and to engage with healds in turn in selected banks close to the heald support in order to restrain said healds against inward shedding movement so that the warp threads whose healds are free are deflected while the warp threads whose healds are restrained remain undeflected.

4. Shedding mechanism for a circular loom, comprising a heald support disposed within the warp circle, a plurality of banks of individually movable flat warp thread controlling healds mounted on their edges within the support and projecting radially outwards therefrom so as to control the warp threads from the inside of the warp circle, means for locking all the healds against radial motion within the support, means between which and the healds there is relative circular motion about the loom axis for urging all the healds into a shedding movement in a radial direction progressively round the loom, and means cooperating with said urging means for unlocking healds in selected banks progressively round the loom to free such healds for shedding movement so that the warp threads whose healds are unlocked are deflected while the warp threads whose healds remain locked remain undeflected.

5. Shedding mechanism for a circular loom, comprising a heald support disposed within the warp circle, a plurality of banks of flat movable warp thread controlling healds mounted on their edges within said support and projecting radially outwards therefrom so as to control the warp threads from inside the warp circle, locking means adapted to engage with recesses in said healds so as to lock all the healds against radial motion within said support, means for urging all the healds into a shedding movement in a radial direction, and a cam co-operating with said urging means and adapted to lift healds in selected banks from contact with said locking means in order to free said healds for shedding movement so that the warp threads whose healds are unlocked are deflected while the warp threads whose healds remain locked remain undeflected.

6. Shedding mechanism for a circular loom, comprising a heald support disposed within the warp circle, a plurality of banks of flat movable warp thread controlling healds mounted on their edges within said support and projecting radially outwards therefrom so as to control the warp threads from inside the warp circle, locking means incorporated in said support and adapted to engage with recesses formed in the lower edges of said healds so as to lock all the healds against radial motion within said support, means for urg-

ing all the healds into a shedding movement in a radial direction, and a cam co-operating with said urging means and adapted to lift healds in selected banks from contact with said locking means in order to free said healds for shedding movement so that the warp threads whose healds are unlocked are deflected while the warp threads whose healds remain locked remain undeflected.

7. Shedding mechanism for a circular loom, comprising a heald support disposed within the warp circle, a plurality of banks of flat warp thread controlling healds mounted on their edges within said support and projecting radially outwards therefrom so as to control the warp threads from inside the warp circle, a rotatable shedding wheel between which and said healds there is relative circular motion about the loom axis, said shedding wheel being adapted to press all the warp threads progressively radially of the loom and thereby to urge all the healds progressively into a shedding movement in a radial direction, and means co-operating with said urging means for restraining healds in selected banks against such shedding movement so that the warp threads whose healds are free are deflected progressively around the loom while the warp threads whose healds are restrained remain undeflected.

8. Shedding mechanism for a circular loom, comprising a heald support disposed within the warp circle, a plurality of banks of flat warp thread controlling healds mounted on their edges within said support and projecting radially outwards therefrom so as to control the warp threads from inside the warp circle, a rotatable shedding wheel between which and said healds there is relative circular motion about the loom axis, said shedding wheel being adapted to press all the warp threads progressively radially of the loom and thereby to urge all the healds progressively into a shedding movement in a radial direction, and a stop co-operating with said shedding wheel and adapted to engage with healds in selected banks so as to restrain said healds against the shedding movement so that the warp threads whose healds are free are deflected while the warp threads whose healds are restrained remain undeflected.

9. Shedding mechanism for a circular loom, comprising a heald support disposed within the warp circle, a plurality of banks of flat movable warp thread controlling healds mounted on their edges within said support and projecting radially outwards therefrom so as to control the warp threads from inside the warp circle, means for locking all the healds against radial motion within said support, a rotatable shedding wheel between which and said healds there is relative circular motion about the loom axis, said shedding wheel being adapted to press all the warp threads progressively radially of the loom and thereby to urge all the healds progressively into a shedding movement in a radial direction, and means co-operating with said shedding wheel for unlocking healds in selected banks to free said healds for shedding movement so that the warp threads whose healds are unlocked are deflected while the warp threads whose healds remain locked remain undeflected.

10. Shedding mechanism for a circular loom, comprising a heald support disposed within the warp circle, a plurality of banks of flat movable warp thread controlling healds mounted on their edges within said support and projecting radially outwards therefrom so as to control the warp

threads from inside the warp circle, locking means adapted to engage with recesses in said healds so as to lock all the healds against radial motion within said support, a rotatable shedding wheel between which and said healds there is relative circular motion about the loom axis, said shedding wheel being adapted to press all the warp threads progressively radially of the loom and thereby to urge all the healds progressively into a shedding movement in a radial direction, and a cam co-operating with said shedding wheel and adapted to lift healds in selected banks from contact with said locking means in order to free said healds for shedding movement so that the warp threads whose healds are unlocked are deflected while the warp threads whose healds remain locked remain undeflected.

11. Shedding mechanism for a circular loom, comprising a pair of concentric cylindrical reed-like members having the same number of dents,

means for mounting said pair of reed-like members inside the warp circle, a plurality of banks of radially disposed individually movable flat warp thread controlling healds supported on their edges between the dents of said concentric reed-like members for protruding therefrom so as to control the warp threads from the inside of the warp circle, means between which and the healds there is relative circular motion about the loom axis for urging all the healds into a shedding movement in a radial direction progressively round the loom, and means co-operating with said urging means for restraining healds in selected banks against such shedding movement so that the warp threads whose healds are free are deflected progressively round the loom while the warp threads whose healds are restrained remain undeflected.
